(57) **CLAIM**

The ornamental design for a thermostat device with mounting plates as shown.

DESCRIPTION

FIG. 1 is a perspective view of the thermostat device with mounting plates.

FIG. 2 is an exploded perspective view of the thermostat device with mounting plates, showing a back plate and a wall trim plate.

FIG. 3 is a front elevation view of the thermostat device with mounting plates.

FIG. 4 is a rear elevation view of the thermostat device with mounting plates.

FIG. 5 is a top plan view of the thermostat device with mounting plates.

FIG. 6 is a bottom plan view of the thermostat device with mounting plates.

FIG. 7 is a left side elevation view of the thermostat device with mounting plates; and,

FIG. 8 is a right side elevation view of the thermostat device with mounting plates.

1 Claim, 4 Drawing Sheets
